UNITED STATES PATENT OFFICE.

EDWARD S. ROOT AND CHARLES S. DEMAREST, OF NEW YORK, N. Y.

VALVE FOR GAS OR OTHER PIPES.

SPECIFICATION forming part of Letters Patent No. 727,205, dated May 5, 1903.

Application filed December 6, 1902. Serial No. 134,097. (No model.)

To all whom it may concern:

Be it known that we, EDWARD S. ROOT and CHARLES S. DEMAREST, citizens of the United States, and residents of the borough of Manhattan, in the city, county, and State of New York, have jointly invented a new and useful Improvement in Valves for Gas or other Pipes, which invention is fully set forth and illustrated in the following specification and accompanying drawings.

The object of this invention is to provide a valve of simple construction for use in pipes conveying gas, oil, ammonia, or other fluids which will automatically close and stop the passage of fluid through the pipes when the temperature rises to a certain point and which can also be closed by hand and locked in its closed position whenever desired.

The valve herein described is an improvement upon or modification of the valve described in Letters Patent No. 679,543, issued to us July 30, 1901.

The invention will first be described in detail and then set forth in the claims.

In the accompanying drawings, Figure 1 is a view in longitudinal vertical section, showing our improved valve as it is applied to a pipe, the valve being shown in its open position. Fig. 2 is a view in plan of Fig. 1. Fig. 3 is a view in side elevation, showing the usual arrangement of a fluid-meter (such as a gas-meter) and its connecting-pipes with our valve in position.

In said figures the number 1 indicates the valve-casing provided with two threaded sockets 2 3 for connection, respectively, to inlet and outlet pipes. Within the casing 1 is inserted a rotary plug-cock 4, having formed therein ports or passage-ways 5 6 for permitting the passage of fluid therethrough. The plug 4 is cast with an open bottom and cored out, as shown, to present a hollow interior, in which is formed an internal valve-seat 7. Inserted within the hollow plug 4 is a lifting-valve 8, provided with an upper valve-stem 9 and with a shorter lower valve-stem 10. The lower stem 10 extends downward through a casing or guide-block 11, which is screwed to the plug 4 within its hollow interior. Said guide-block 11 serves as a guide for the valve-stem 10 and is provided on its upper surface with

a recess 12, adapted to receive a coiled spring 13, which surrounds the stem 10. The upper valve-stem 9 extends upward through a hole in the top of the plug 4 and through a nut 14 cast thereon, the upper part of the nut 14 being hollowed out, as shown, so as to form a bonnet or casing 15 for the upper end of the stem 9. The casing 15 is screw-threaded, as shown, and upon it is screwed a removable cap composed of two parts 16 17. The part 16, which engages the top of the valve-stem 9 and forms a bearing-plate therefor when the valve is open, is secured to the part 17 at the point *a* by solder fusible at a temperature of about 150° Fahrenheit.

The lower end of the plug 4 is screw-threaded to receive a nut 18, which, in connection with a washer 19, forms a tight joint at the end of said plug. The top of the plug 4 has cast thereon a lug 20, provided with a hole 21, and said lug when the plug 4 is in its closed position registers with a corresponding locking-lug 22, cast upon the valve-casing 1 and provided with a hole 23. By passing a lock through the holes 21 23 the plug will be locked in its closed position.

The various parts are assembled by inserting the valve 8, with its stems 9 10 and spring 13, within the hollow plug 4 and screwing into place the guide-block 11, thus closing the valve 8 in its seat 7. The upper valve-stem 9 will then project into and above the casing 15, and by screwing into place the fusible cap composed of the two parts 16 17 the contact between the part 16 and the valve-stem will, as the cap is screwed into place, force the stem 9 and the valve 8 downward, compressing the spring 11 and opening said valve for the passage of fluid. If the plug 4 be rotated, by means of a wrench applied to the nut 14, into the open position shown in Fig. 1, a clear passage-way will thus be formed for the passage of fluid through its ports 5 6 and past the valve 8.

The valve may be placed in any desired position in a line of pipe; but if used in connection with gas-pipes and a gas-meter it should be placed, as shown in Fig. 3, in the gas-supply pipe 24, leading to the gas-meter 25. The discharge-pipe or house supply-pipe is indicated at 26, the number 27 indicating

the lead-pipe connections, which are usually employed for connecting the pipes 24 26 with the meter 25.

The operation of the valve is as follows:

- 5 When the temperature has risen (owing to the breaking out of a fire in the vicinity of the valve) to the melting-point of the solder employed in the fusible cap 16 17, said solder will fuse, and the bearing-plate 16 of said cap 10 in contact with the valve-stem 7 will be forced off the part 17 by reason of the spring 13 being released from compression. Said spring will thus instantaneously force the valve 8 into its seat 7 and cut off all passage 15 of gas or other fluid through the pipe 24 and through both valves 4 8. If, therefore, the valve be placed as shown in Fig. 3, it will have automatically closed before the heat of the fire has reached the point sufficient to 20 melt the meter 25 or any of the lead-pipe connections 27, and no subsequent destruction of the meter or lead pipes will allow gas to escape into the building. In order to reset the valve 8 after it has closed automatically, it 25 is only necessary to solder a new bearing-plate 16 upon the part 17 of the cap and rescrew the cap upon the casing 15.

- 30 If it be desired, as is sometimes necessary, to cut off by hand the supply of fluid through the pipe 24, a wrench is applied to the nut 14 on the plug-cock 4 and said plug rotated until its ports 5 6 are no longer in line with the openings 2 3. This will stop the passage of all fluid through the plug 4 and through the 35 valve 8, and if the locking-lugs 20 22 be secured together by a lock the whole valve is locked and the pipe closed to the passage of fluid until the plug 4 is again turned by hand into its open position. The automatic valve 40 8 may also be closed by hand whenever desired by simply unscrewing the cap 16 17 from the casing 15, and by replacing said cap the valve will be reopened.

- 45 From the above description it will be seen that our valve structure consists, essentially, of two valves, one located within the body of the other, one of said valves being adapted to be opened and closed by hand and the other adapted to be opened by hand and closed automatically. A combined valve so arranged possesses all the advantages of the valve described in our former patent above referred to and in addition presents all the advantages gained by the use of a rotary plug-cock, which is regarded by many as the most efficient type of valve for cutting off by hand the supply of gas and other fluids through 50 pipes.

- 55 We do not limit ourselves to the precise construction and arrangement of the several parts shown, as it is evident that such construction and arrangement may be varied without departing from the essence of our invention.

- 60 65 Having thus fully described our invention, we claim—

1. In a valve structure, the combination of

a hollow hand-operated valve, having a transverse valve-seat on its interior; and an automatic valve located within said hand-operated 70 valve.

2. In a valve structure, the combination of a hollow rotary valve having a transverse valve-seat on its interior; a lifting-valve within said rotary valve; and means for closing 75 15 lifting-valve automatically.

3. In a valve structure, the combination of a valve-casing provided with inlet and outlet openings; a hollow rotary plug within said casing, provided with an internal transverse 80 valve-seat; a valve within said plug, provided with a stem; and fusible means for engaging said stem and holding said valve open.

4. In a valve structure, the combination of a valve-casing provided with inlet and outlet 85 openings; a hollow rotary plug, within said casing, provided with an internal valve-seat; a valve within said plug, provided with a stem; and a bearing plate or support, for holding 90 said valve open, secured in place by fusible metal.

5. In a valve structure, the combination of a valve-casing provided with inlet and outlet openings; a hollow rotary plug within said casing, provided with an internal transverse 95 valve-seat; a valve within said plug, provided with a stem; a spring surrounding said stem; and fusible means for engaging said stem and holding the valve open against the pressure of said spring. 100

6. In a valve structure, the combination of a valve-casing provided with inlet and outlet openings; a hollow rotary plug within said casing provided with an internal valve-seat; a valve within said plug provided with a stem; a spring surrounding said stem; and a bearing plate or support, for holding said valve open against the pressure of the spring, secured in place by fusible metal. 105

7. In a valve structure, the combination of a valve-casing provided with inlet and outlet openings; a hollow rotary plug within said casing provided with an internal valve-seat; a valve within said plug provided with a stem; a bonnet for said stem; and a cap for said 115 bonnet, provided with a bearing-plate for said valve-stem, said bearing-plate being secured to the cap by fusible metal. 110

8. In a valve structure, the combination of a valve-casing provided with inlet and outlet 120 openings; a hollow rotary plug within said casing, provided with an internal valve-seat; a valve within said plug provided with a stem; a spring surrounding said stem; a bonnet for the stem; and a cap for said bonnet, provided 125 with a bearing-plate for said stem, said bearing-plate being secured to the cap by fusible metal.

9. The combination of a valve-casing provided with inlet and outlet openings; a hollow rotary plug within said casing provided with an internal valve-seat; a valve within said plug provided with a valve-stem on each side; a spring surrounding one of said stems 130

and tending to close the valve; and fusible means for engaging the other valve-stem and holding the valve open against the pressure of the spring.

5 10. The combination of a valve-casing provided with inlet and outlet openings; a hollow rotary plug within said casing provided with an internal valve-seat; a valve within said plug provided with a valve-stem on each side; a spring surrounding one of said stems and tending to close the valve; a bonnet for

the other valve-stem provided with a cap; and a bearing-plate, secured to said cap by fusible metal, for engaging the other valve-stem and holding the valve open against the pressure of the spring. 5
